UNITED STATES PATENT OFFICE.

ROBERT COATS KENNEDY, OF WALSEN, COLORADO.

MASON'S SCOTCH.

Application filed July 15, 1919. Serial No. 310,879.

To all whom it may concern:

Be it known that I, ROBERT C. KENNEDY, a citizen of the United States, residing at Walsen, in the county of Huerfano, State of Colorado, have invented certain new and useful Improvements in Masons' Scotches; and I do hereby declare the following to be a full, clear, and exact description of the invention, such as will enable others skilled 10 in the art to which it appertains to make and use the same.

This invention relates to new and useful improvements in masons' tools and particularly to scratching tools known as scotches.

15 One object of the present invention is to provide a novel and improved means for securing the head on the handle.

Another object is to provide a novel and improved structure of this character which 20 is simple in its construction and strong and durable as well as effective in its operation.

Other objects and advantages will be apparent from the following description when taken in connection with the accompanying 25 drawing.

In the drawing:

Figure 1 is a side elevation of the tool.

Figure 2 is an enlarged vertical sectional view taken on the line 2—2 of Figure 1.

30 Figure 3 is a vertical sectional view taken on the line 3—3 of Figure 2.

Figure 4 is an enlarged horizontal sectional view taken on the line 4—4 of Figure 1, looking downwardly in the direction of the 35 arrows.

Figure 5 is an inverted perspective view of the head of the tool removed from the handle.

Referring particularly to the accompanying drawing, 10 represents the head of the tool, which is in the general form of a pick head, and has the central enlarged or thickened portion 11. In this portion 11, and extending from the inner end to a point adjacent the outer intermediate portion of the head, is a recess which includes the outer elongated portion 12, extending longitudinally of the head, and the substantially circular bore 13, extending at right angles to the portion 12. In opposite sides of this bore, the walls are longitudinally slotted, as shown at 14 for the reception of the cylindrical stem 15, of the handle. On the end of the stem 15, which enters the head, there

are formed the two oppositely extending 55 radial lugs 16, said lugs being of a width to easily slide longitudinally through the slots 14, of the head. In inserting the member 15 into the head, said member is turned so that the lugs will enter the opposite slots 14, 60 when the stem is pushed into the head, and when the lugs reach a position inwardly of the shoulders 17, formed between the portion 12 and the bore, the stem is turned until the lugs lie within the said portion 12 with their 65 side faces flush with the side faces of the enlargement of the head. In the inserted end of the stem 15 there is formed a recess 18 which receives the inner end of the set screw 19 which is disposed through the center of 70 the head.

The other end of the metal stem 15 is formed with a socket, as shown at 20 and in the side walls of the socket there are formed aligning openings 21. Disposed in the socket 75 is one end of the wooden hand grip 22, rivets 23 being passed through the aligned openings and through said grip to hold the same firmly therewithin.

What is claimed is:

In a device of the class described, a head, a tubular extension formed integral with said head and projecting at right angles thereto, the said head having a recess in communication with the hollow part of said extension, the recess of said head extending into the medial portion thereof and being enlarged at its base at diametrically opposite points, the said extension being cut away upon its opposite sides and longitudinally to provide slots co-extensive with said extension and communicating with said enlarged recess of the head, a handle of a size to snugly fit in said tubular extension, radially disposed lugs at the extreme inner end 95 of said handle, said inner end being of a width to permit its passage through said slots and of a length and thickness to snugly engage the recess in the head upon a quarter turn of said end, and means for frictionally holding said handle in said head.

In testimony whereof, I affix my signature, in the presence of witnesses.

ROBERT COATS KENNEDY.

Witnesses:
